UNITED STATES PATENT OFFICE

99,921

DESIGN FOR AN ASHTRAY

Albert E. Adams, Scranton, Iowa

Application April 2, 1936, Serial No. 61,914

Term of patent 3½ years

To all whom it may concern:

Be it known that I, Albert E. Adams, a citizen of the United States residing at Scranton, in the county of Greene and State of Iowa, have invented a new, original, and ornamental Design for an Ashtray, of which the following is a specification, reference being had to the accompanying drawing, forming part thereof.

Figure 1 is a plan view of an ashtray, showing my new design.

Figure 2 is a front elevation.

Figure 3 is a section on line 3—3, Figure 1.

Figure 4 is a section on line 4—4, Figure 1.

I claim:

The ornamental design for an ashtray, as shown..

ALBERT E. ADAMS.
